POSITIVE LOADING SCRAPER

Stanley S. Moore, Stockton, Calif.

Application March 21, 1938, Serial No. 197,068

10 Claims. (Cl. 37—128)

This invention relates to tractor drawn carrying scrapers of large capacity, the major object of the invention being to provide dirt handling mechanism in the scraper so arranged that without any undue expenditure of power, the scraper may be readily and positively loaded to its actual or theoretical capacity, and this may be accomplished whether the dirt is of the relatively inert or live variety. This I believe is in contra-distinction to all scrapers of this general type of which I have any knowledge and which cannot be practicably loaded, by a scraping operation, to within several yards of their possible capacity. In other words, the operator of a scraper constructed and built sufficiently strong to hold twenty yards of dirt for instance is only able in practice to load about fifteen yards thereon, and with certain kinds of dirt, even this yardage is unattainable. As a result, the deadweight load which must be hauled by the tractor is out of proportion to the pay load. With my improved scraper on the other hand, this disadvantageous and expense and inefficient form of operation is definitely avoided.

This major object is attained by what I term a load crowder, which is movable at the option of the operator to engage the dirt being taken in at the scraping end of the body or bowl of the scraper, and to literally shovel or scoop up such dirt and dump the same into the rearmost portion of the bowl.

In connection with this crowder, it is another object of my invention to so mount the same that its movement either advancing or returning to its normal position (where it serves as a dirt retainer) does not interfere with the continued feeding or passage of dirt into the front end of the bowl. In other words, there need be no interruption to the continuous forward movement and scraping action of the scraper even when the crowder is being manipulated. Not only may a full load be taken on, but such loading may be accomplished with no delays and hence in a minimum of time.

The scraper bowl is arranged to be discharged, for spreading or dumping, by the upward movement of the forward end of the bowl. In connection with such general arrangement, it is an object of the invention to provide for the initial creation of an opening for the discharge of the dirt by such upward movement of the bowl only when the latter has been raised beyond a predetermined point, and to cause such opening to be automatically increased in extent by the further lifting of the bowl. Also, the discharging move-

ment of the bowl does not in any way affect or interfere with the crowder previously mentioned, which may be used if desired to facilitate or speed up the dirt discharging operation.

A further object of the invention is to provide what I believe to be a novel form of connection and mounting means for the front end of the bowl, and a novel control device for tilting the bowl incorporated with said connection means.

These objects I accomplish by means of such structure and relative arrangement of parts as will fully appear by a perusal of the following specification and claims.

In the drawings similar characters of reference indicate corresponding parts in the several views: 15

Figure 1 is a side elevation of the scraper in carrying position.

Figure 2 is a top plan view of the same.

Figure 3 is a sectional elevation of the scraper in digging position.

Figure 4 is a similar view showing the scraper as dumping.

Figure 5 is a fragmentary longitudinal section of the scraper in a loading or digging position, showing various positions of the crowder.

Figure 6 is an enlarged fragmentary section on line 6—6 of Figure 3.

Figure 7 is a similar view on line 7—7 of Figure 4.

Referring now more particularly to the characters of reference on the drawings, the body of the scraper comprises side plates 1 depending from longitudinal hollow top beams 2 and reinforced by other beams 3 which include a peripheral framework, all of said beams being on the outside of the plates. At the front and top the side plates are connected by a cylindrical tubular beam 4 and adjacent the rear end by another crossbeam 5. Rearwardly of the beam 5, the side plates are supported by pairs of dual wheels 6 the axles 7 of these wheels forming the pivotal axis about which the scraper as a whole may tilt.

Depending from the beam 4 centrally of its extent is a post unit 8, which supports a vertical king pin 9. This is mounted on a fifth wheel unit 10 which includes a longitudinal pin 11. Swivelly mounted on this pin is a collar 12 carrying a transverse pin 13. The pin 13 is supported in the rear ends of a forked draft tongue 14, provided at its forward end with a swivel clevis 15 adapted for connection to the drawbar of a tractor and hence held at a fixed level. The tractor can thus turn about the clevis, and the tongue and front wheel unit can swivel about the pin 9 55

while assuming any lateral or longitudinal angle relative thereto as the ground contours may necessitate.

5 Adjacent its forward end, the tongue is turn-
ably supported on a transverse pin 16 which is
mounted in rearwardly projecting frames 17.
These extend to the sides of and beyond the
tongue, clearing the forked end of the latter, and
adjacent their rear end support wheels 19 whose
10 axis lies in a vertical plane close to that of pin
9. At their rear end, the frames are connected
by a crossbeam 20, and a head of the wheels
support. An upstanding rectangular yoke 21
whose top and bottom cross beams, above and
15 below the tongue respectively, also serve to con-
nect and brace the frames against spreading.

A sheave-block 22 is supported at the top of
the yoke, while a corresponding block 23 is mount-
ed on the tongue at the inception of its fork.

20 A cable 24 extends from a power unit on the
tractor to the upper sheave-block from between
fair-lead rollers 25 on the yoke, and then passes
between the sheaves of the two blocks to a suit-
ably located dead end.

25 It will thus be seen that a pull on the cable
will lift the tongue, the latter turning on pin
16, and the scraper will be lifted about the rear
wheels 6 as an axis, the arms 17 remaining in
substantially the same position at all times.

30 Extending between the side plates toward the
front thereof is a rigid blade 26, fixed with and
extending rearwardly from which a relatively
short distance is a bottom plate 27. Swung from
the side plates rearwardly of plate 27 on trun-
35 nions 28 is the main spreader bowl and endgate
29. This bowl is of curved form and is adapted
at its forward end to form a closure with the
rear edge of plate 27, its upper end being then
close to the top of the side plates 1 as shown
40 in Fig. 3. The trunnions 28 are some distance
above and rearwardly of this rear edge so that
as the bowl swings back to open a gap between
the fixed plate 27, its forward edge moves down
45 for the first portion of the swinging movement
of the bowl.

Such swinging movement is imparted to the
bowl simultaneously with the lifting of the scrap-
er above a carrying position by the following
means: Fixed on the back of the bowl well be-
50 low the trunnions 28 is a cable 30. This passes
upwardly about a pulley 31 mounted on an arm
32 upstanding from the cross-beam 5. From this
pulley the cable 30 passes about another pulley
33 fixed in one of the upper beams 2 (see Fig.
55 2). The cable then extends forwardly inside
said beam leaving the same adjacent its forward
end about another pulley 34. Said cable then
passes about another pulley 35 hung from beam
4, down about a pulley 36 mounted on the cross-
beam 20 of the wheel frame, and up to a dead
60 end on said beam 4. The cable 30 is slack be-
tween digging and carrying positions of the
scraper, and the corresponding difference in dis-
tance between crossbeams 4 and 20. With fur-
ther lifting of the scraper and crossbeam 4 how-
65 ever (by a pull on cable 24), the cable 30 be-
comes taut, and the length of the cable runs
between pulleys 35 and 36 is increased. Since
the cable is of fixed length, this causes the bowl
70 to be pulled upwardly at the back causing a
discharge or spreading gap to be opened between
said bowl and the fixed plate 27. The extent
of movement thus imparted to the bowl is in pro-
portion to the amount of lift imparted to the
scraper, and the width of the gap is also pro-

portionate to such lift. Since the forward edge
of the bowl drops with its initial opening move-
ment for the reason previously set forth, the
distance between such edge and the ground will
be initially decreased somewhat so that the rela-
tively small discharge opening then had goes
with the thin spread allowed by this position of
the bowl. As the scraper is lifted higher and
the gap is widened, the spreading depth auto-
matically increases in proportion to the increase 10
in the width of the gap and the greater amount
of dirt being discharged. In any event, the
lower edge of the bowl when turned from a clos-
ing position always projects below the fixed plate
27 to serve as a leveling blade. When the tongue 15
has been raised to its limit, as determined by the
approach of sheave-blocks 22 and 23 toward each
other, the bowl is then practically inverted, and
the discharge gap is of maximum width, thus
providing for a complete discharge from the 20
bowl and a rapid discharge from the bowl as a
whole. Due to the position of the bowl trun-
nions 28 relative to the distribution of weight
of the bowl, whether light or loaded, there is a
tendency for the bowl to swing open of itself. 25
To counteract and overcome this tendency, radial
depending arms 37 are secured on the outer ends
of the trunnions (see Fig. 1). These are con-
nected by pull rods 38 or the like with the lower
30 ends of levers 39 which project upwardly through
beams 2 to pivotal mountings 40 above said
beams, the latter being longitudinally slotted to
permit of the swivel movement of said levers.
Inside the beams the levers are acted on by
heavy springs 41 positioned to force the levers 35
forwardly and thus, through their connection
with the bowl, yieldably hold the bowl in a closed
position.

In order to enable the scraper to be readily
loaded to its actual full capacity when operating 40
in any kind of dirt and without excessive pulling
strains on the draft tongue or tractor, and with-
out halting the forward movement of the scraper
at any time, I provide the following structure:
Disposed in facing relation to the bowl 29 is an 45
upstanding or substantially vertical crowder or
loader scoop 42 having side plates 43 fitting be-
tween the side plates 1. This crowder is rigidly
mounted on side bars 45 which extend rearward-
ly from the plates 43 at the top. At their rear 50
ends, the bars are pivoted on depending swing
arms 46 turnably mounted at their lower ends
on the trunnions 28 between the arms 37 and the
side plates 1. The arms 46 are connected above
the plates 1 by a crossbeam 47 so as to tie them 55
together as a rigid unit. The length of bars 45
is such that when the arms 46 are disposed at
a forward slope of approximately 45°, the crowder
is some distance in front of blade 26.

Movement of the crowder is controlled by a 60
single cable 48 from the power unit on the trac-
tor. This extends about guide pulleys 49 and 50
on the post 8 and the side beam 2 opposite that
on which pulley 34 is mounted (see Fig. 2), then
along said side beam, and over fixed guide pul-
leys 51 mounted adjacent the back of the scraper.
From there the cable passes back and forth be-
tween sheave-blocks 52 and 53 respectively,
mounted on the adjacent bar 45 and the adja-
cent one of posts 54 upstanding from the cross-
beam 5, the block 52 being ahead of block 53.
Said cable then passes about a guide pulley 55
on said one post, through a conduit 56 connect-
ing said one pulley with another like pulley 57
on the other post 54.

From there the cable passes back and forth between the sheaves of blocks 52a and 53a mounted respectively on the other bar 45 and the other post 52, to a dead end adjacent the latter. It will thus be seen that a pull on the cable 48 pulls rearwardly on both bars 45 simultaneously and to the same extent, also of course pulling the crowder back and finally up, since the sheave-blocks 53 and 53a are considerably higher from the bottom of the scraper than the height of the crowder.

During its movement rearwardly from a position in substantial engagement with the blade 26, the crowder is free for either horizontal or vertical movement, thus enabling it to either remain in dragging contact with the plate 27, or to lift over a pile of dirt thereon, much in the manner that a hand rake being pulled will ride over a pile when such pile offers excessive resistance to the pull on the rake.

Rearward movement of the crowder is limited by the engagement of the crossbeam 47 with the posts 54, while upward movement of the crowder is limited by the engagement of the sheave-blocks 52 and 53 with each other, or by the use of other equivalent stop means. Downward and forward movement of the crowder from this position however is guided along a definite path by the following means: Formed in each side wall structure of the scraper from its inner face is a track-groove which includes a straight portion 58 disposed at a forward and downward slope from an open inception some distance above the top of the side plates 1. The upper end of said straight portion is in position to be directly under a roller 59 mounted on the adjacent side plate 43 of the crowder when the latter is in its rearmost and topmost position as shown in Fig. 5. An upper extension 1a of each side plate 1 extend to the top of the track groove rearwardly of the same.

The roller is mounted for lateral as well as rotating movement and is yieldably urged out by a spring 60 mounted in a housing 61 formed in the crowder. The lower end of the straight track portion 58 is some distance in front of the blade and terminates in a seat 62 for the roller. This seat is positioned at such a height that when the roller is seated, the lower edge of the crowder is still some distance above and in front of the scraping blade as shown in Fig. 5, or in a proper position to cooperate with the blade when digging to receive and retain some of the dirt being scraped up.

Depending from the roller seat with a rearward and downward slope from an inception slightly above the bottom of the seat is a final track portion 63 which gradually feathers out in depth to merge into the flat surface of the side plate 1; as shown in Fig. 6. This point of emergence is positioned so that the roller is clear of the track by the time the crowder engages the blade 26.

The operation of the crowder from the normal loading position of the scraper shown in Fig. 3 is as follows: As the dirt is piling upon the blade and fixed plate 27 with the forward movement of the scraper, the cable 48 is first given a slight pull to withdraw the rollers 59 from their seats 62, and is then released momentarily so that the rollers will move down the track portion 63. The pull on the cable is then continued until the rollers move clear of the tracks (retracting into the crowder as they do so as shown in Fig. 7) and until the crowder is moved to its rearmost and up-

permost position as shown in Fig. 5. With such movement of the crowder the rollers merely bear against the smooth untracked portion of the side plates 1, so that the crowder is free to either push all the dirt engaged thereby rearwardly into the bowl 29, or leave some of the dirt piled up and merely ride up over the same.

When the crowder has reached its topmost position, the rollers are clear of the side walls and extensions 1a, and have sprung out into a track 10 engaging position. The pull on cable 48 is then released, and the crowder then drops of its own weight, the rollers engaging the track portions 58 and guiding the movement of the crowder in a forward direction until the rollers again engage the seats 62.

The operation may then be repeated until all possible dirt being scraped up has been crowded back into the bowl 29 and the structure has been loaded to capacity. With any such manipulation 20 of the crowder, it will be seen that no interference with the continued forward movement of the scraper and loading of the dirt is had, since on its back stroke the crowder is moving away from the incoming dirt, while on its forward stroke, it 25 is above and clear of the zone of the dirt.

When the scraper is loaded and it is desired to carry the load, the crowder is lowered and pulled back until it engages the blade 26, thus confining all the dirt within the confines of the crowder, 30 fixed plate 27, rear bowl 29 and side plates 1. Since the plate 27 never deviates greatly from a horizontal position, the crowder is also employed in unloading or dumping operations, the rearward movement of the crowder then causing all 35 dirt on the plate 27 to be shoveled off said plate and into the discharge gap then formed between the plate 27 and rear bowl 29 as previously explained.

From the foregoing description it will be readily 40 seen that I have produced such a device as substantially fulfills the objects of the invention as set forth herein.

While this specification sets forth in detail the present and preferred construction of the device, 45 still in practice such deviations from such detail may be resorted to as do not form a departure from the spirit of the invention, as defined by the appended claims.

Having thus described my invention, what I 50 claim as new and useful and desire to secure by Letters Patent is:

1. A scraper including a body, wheels supporting the body at the back and about which said body is tiltable, said body including a fixed blade 55 and bottom plate unit, an endgate disposed rearwardly of the fixed plate and adapted at its forward end to normally form a closure with the rear end of said fixed plate, means mounting the endgate for swinging movement rearwardly 60 from a closure forming position to provide a discharge gap, means to tilt the body upwardly about the wheels and means functioning with such tilting of the body beyond a predetermined position to thus swing the endgate; said last 65 named means comprising a wheel supported frame at the front of the scraper and whose level relative to the ground is substantially constant, a cable of fixed length anchored at its forward end on the body adjacent its forward end and at its 70 rear end on the endgate at a point thereon such that a pull on the cable will swing the endgate rearwardly, and means between the wheel supported frame and the cable to cause such pull to be imparted to the cable only upon upward move- 75

- ment of the front end of the body beyond a predetermined level.
2. A structure as in claim 1 in which said last named means comprises a pulley fixed on the 5 wheel supported frame below the anchored end of the cable and about which the cable passes from said end, and another pulley on the body above the first named pulley and about which the cable passes from said first named pulley; 10 the cable then extending rearwardly to the bowl.
3. A scraper comprising a wheel supported body which includes side plates, a fixed blade and bottom plate unit mounted between the side plates, an endgate disposed rearwardly of the 15 fixed plate and adapted at its forward end to normally form a closure with the rear end of the fixed plate, trunnions rigid with the endgate above the bottom thereof and turnably projecting through the side plates whereby the endgate 20 may be swung, means to swing the endgate rearwardly from a closure forming position, side beams on the body outwardly of and along the top of the side plates, radial arms depending from the trunnions outwardly of the side plates, other 25 arms disposed ahead of said radial arms and projecting upwardly through the beams, means pivotally mounting the last named arms on the body above the beams, links connecting the corresponding arms at their lower ends, and springs 30 enclosed within the beams and acting on the last named arms to swing the same forwardly.
4. A scraper comprising a wheel supported body which includes side plates, a fixed blade and bottom plate unit mounted between the side 35 plates, an endgate disposed rearwardly of the fixed plate and adapted at its forward end to normally form a closure with the rear end of the fixed plate, trunnions rigid with the endgate above the bottom thereof and turnably projecting 40 through the side plates whereby the endgate may be swung, means to swing the endgate rearwardly from a closure forming position, radial arms rigid with the trunnions outwardly of the side plates, and springs acting on said 45 arms to turn the same in a direction to swing the endgate forwardly.
5. In a scraper, a body having a dirt retaining structure therein, wheels supporting the body at its rear end, front wheels ahead of the body, 50 spaced side frames supported by the front wheels and disposed inwardly of the wheels, a draft tongue disposed between the frames, means pivoting the tongue on the frames at the forward end of the latter, the tongue being adapted at its 55 forward end for supporting connection with a tractor, a supporting connection between the tongue and the front end of the body, and means to swing the tongue about its pivot.
6. In a scraper, a body having a dirt retaining structure therein, wheels supporting the body at its rear end, front wheels ahead of the body, spaced side frames supported by the front wheels and disposed inwardly of the wheels, a draft tongue disposed between the frames, means pivoting the tongue on the frames at the forward 10 end of the latter, the tongue being adapted at its forward end for supporting connection with a tractor, a supporting connection between the tongue and the front end of the body, and means applied to the tongue rearwardly of its pivot to 15 pull the same upwardly.
7. A structure as in claim 5, in which said supporting connection comprises a post depending from the front end of the body and overhanging the rear end of the tongue, and a fifth wheel 20 and universal joint unit connecting said post and tongue.
8. A structure as in claim 6, in which said last named means comprises an upstanding yoke rigid with the frames and including a crossbeam 25 above the tongue, sheave-blocks on said crossbeam and tongue and a pull cable extending from in front of the yoke to the adjacent sheave-block and then back and forth between the 30 blocks.
9. A structure as in claim 6, in which said last named means comprises an upstanding yoke rigid with the frames and including a crossbeam above the tongue, sheave-blocks on said crossbeam and tongue and a pull cable extending 35 from in front of the yoke to the adjacent sheave-block and then back and forth between the blocks, and vertical fair-lead rollers on the yoke guiding the cable to the initial sheave of the adjacent block. 40
10. In a scraper, a body having a dirt retaining structure therein, wheels supporting the body at its rear end, a draft tongue adapted at its forward end for supporting connection with a tractor, a post depending from the front end 45 of the body and overhanging the rear end of the tongue, a universal swivel connection between the post and tongue, a front wheel truck pivotally connected to the tongue for relative vertical movement, and means between the truck 50 and tongue for controlling the vertical movement of the tongue whereby to control the raising and lowering tilting movement of the body about the rear wheels as an axis.

STANLEY S. MOORE. 55
